(57) **CLAIM**

The ornamental design for a handheld bidet, as shown and described.

DESCRIPTION

FIG. 1 is a perspective view of the handheld bidet showing my new design;

FIG. 2 is another perspective view of the handheld bidet showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view of portion 9 in FIG. 1.

The dash-dot broken lines in the drawings depict portions of the handheld bidet that forms no part of the claimed design. The dash-dot broken lines in the drawings denote the boundaries of the enlarged detail view and form no part of the claimed design.

1 Claim, 9 Drawing Sheets
